HENRY G. FISKE, OF SPRINGFIELD, MASSACHUSETTS

Letters Patent No. 90,519, dated May 25, 1869.

IMPROVEMENT IN APPARATUS FOR LIGHTING GAS.

The Schedule referred to in these Letters Patent and making part of the same

To all whom it may concern:

Be it known that I, HENRY G. FISKE, of Springfield, in the county of Hampden, and State of Massachusetts, have invented certain new and useful Improvements in Apparatus for Lighting Gas, which I denominate an "Improved Gas-Lighter;" and I do hereby declare that the following is a full, clear, and exact description thereof, reference being had to the accompanying drawings, making a part of this specification, and to the letters of reference marked thereon, in which—

Figure 1 is a side view of a gas-burner, with my invention applied;

Figure 2 is another side view of the same;

Figure 3 is a vertical section, through line P Q of fig. 1;

Figure 4 is a plan view of the armature-chamber, with a portion of the magnet and the spiral valve-spring;

Figure 5 is a side view of the valve-chamber;

Figure 6 is a side view of the burner-insulator;

Figure 7 is a side view of the armature-chamber, showing the apertures for the insertion of the ends of the magnet;

Figure 8 is a plan view of the wire-insulator;

Figure 9 is a reverse plan of the same;

Figure 10 is a plan view of the magnet-insulator;

Figure 11 is a plan view of the adjusting-nut;

Figure 12 is a side view of one modification of the valve;

Figure 13 is a plan view of the same;

Figure 14 is a reverse plan view of the same;

Figure 15 is a side view of another modification of the valve;

Figure 16 is a plan view of the same;

Figure 17 is a reverse plan of the same; and

Figure 18 is a vertical section of the valve-case, through line R S of fig. 5.

My invention relates to the application and use of electro-magnetism, or electricity, or both, in connection with a gas-burner, for the purpose of admitting the gas into and through the burner, and lighting the same; and

It consists in the construction, arrangement, and operation of a valve, gas-burner magnet, and other parts, whereby the gas may be turned on, or be permitted to pass through and out of said burner, or any number of them, and lighted all at the same instant, nearly, and the whole controlled by one person, stationed at any distance from said burner or burners.

That others skilled in the art may be able to make and use my invention, I will proceed to describe its construction and mode of operation.

In the drawings—

B represents an ordinary piece of brass tube, or pipe, having a screw-thread, B', cut upon its lower part, and also having a passage, y, therein.

At r, the passage y terminates in a shoulder, above which the passage widens into the chamber v, which extends upward to the shoulder z.

Above this said shoulder z, the chamber is still more enlarged, and forms the armature-chamber A, which is within the case A², at the upper part of which case, and upon the inside, is cut a female-screw thread.

Apertures, A¹, are also made in said case A², one upon each side, and directly opposite each other.

I represents the valve-case, and is made of brass or other suitable metal, the lower portion being made somewhat larger than the upper part, and male-screw threads f and g cut thereon, the thread g, on the lower portion, fitting the thread cut upon the inside of the case A².

The lower portion of the piece, or case I, has the chamber l therein, the upper part h of which is conical, or in the form of a truncated cone, and forms the seat of the valve; and above the seat h, and communicating with the chamber l, is the passage, or orifice f.

The nut H, which is of suitable thickness, is perforated, and has a screw-thread cut therein, which fits the screw-thread g, upon the lower and larger part of the piece I.

The wire-insulator E is made of any suitable substance which is a non-conductor of electricity, of suitable thickness, and having the perforation, or aperture t therein, through which is inserted, or protrudes the upper part of the valve-case I.

A circular portion is cut away, leaving an annular space, or channel t around the aperture t, into which annular space the top of the large or lower part of the valve-case I protrudes, when it may be drawn upward by the adjusting-nut H.

The apertures s s are also made near each end of the insulator, into which pass the wires L L.

The burner-insulator E' is cylindrical in form, with in the lower and larger part of which is a chamber, and a screw-thread is cut upon the inside of said insulator, which fits the screw-thread f upon the upper and smaller part of the case I; and the upper and smaller part of said insulator has a screw-thread made thereon, which fits the screw-thread made in the lower part of the burner G, and a passage, or orifice, z², extends from the chamber in the said insulator upward, to the top of said insulator, affording an unobstructed passage of gas through the insulator, when in operation.

By this method of insulating the burner and lighting-wires b, I am enabled to use a single wire for the purpose of lighting, which wire may be attached to the insulator E', the spark, or current of electricity passing from the point of said wire, through the gas, to the top of the burner, and from thence to the next insulated wire, by means of a wire attached to said

burner, and extending to the next insulated wire, and so on.

This construction and arrangement lessens the cost of this apparatus, as compared with others in use, as it dispenses with one wire, and the size of the insulator *E* can be reduced, only one insulator being required for both the wire *b* and burner, while its operation is as certain as if two wires were used.

It is also immaterial what kind of burner is used, as a metallic tip is equally as operative as a lava tip, and, indeed, I prefer to use a metallic burner.

By insulating the burner in this manner, I am enabled, in using any kind of burner, to use only one wire from the coil to the burners, and to the last burner I attach a wire, passing it below the insulator, and attaching it to the pipe, connection being made at the other end of the pipe with the coil, so that I make the pipe serve as the return wire for the greater part of the distance.

If very many burners having lava tips were to be lighted by electricity, and the aggregate distances or spaces between the lighting-wires amounted to more than twice the distance between the lighting-wire and the metal portion of the burner, past the lava, the spark, or current would then probably refuse to pass on through these aggregate spaces, and would take the shortest aggregate distance, or pass from the lighting-wire, directly past the lava, to the metallic portion of the first burner, then pass through the pipe to the last burner, pass from that to the last lighting-wire, and from thence back to the coil.

The use of the insulator *E* in insulating the burner and lighting-wire *b*, as herein described, removes the possibility of such a result, and insures a prompt and perfect lighting of all the burners in the series.

The burner *G*, or jet, is of the usual construction, and may be of any of the different varieties manufactured, and is too well known to need any further description.

The valve *o* is cylindrical in form, having the annulets, or annular projections *k* *k'* thereon, which serve as guides to keep the valves always in a proper vertical position, and to the lower end is firmly secured, by soldering, brazing, or otherwise, the disk *m*, which should be made of soft wrought-iron, and forms an armature for the magnet, while that portion of the valve above the disk *m* should be made of brass or other non-magnetic substance.

The upper end *h'* of the valve *o* is, in form, a truncated cone, made to fit nicely the seat *h*, in the valve-case *I*.

The passage, or orifice *i* is made through the disk *m*, and up through the body of the valve, to a point near its upper end, where said passage communicates with two side passages leading out at the side of the valve, near its top.

In figs. 12, 13, and 14, another modification of the valve is shown, in which the central passage *i* is omitted, and small side passages *i'* *i'* are made in the annular projections *k* *k'*, for the escape of the gas.

The magnet-insulator *F* may be of any suitable and convenient length, and having the aperture *e* therein, in which is made a female-screw thread, which fits properly the male-screw thread *B'*, upon which the said insulator *F* is placed.

The bar *D'* has an aperture therein, into which passes or is inserted the pipe *B*, said bar *D'* resting upon the insulator *F*, when both are in place; and the bar *D'* has also the two uprights *D D* of soft iron attached thereto, or they may be made solid with the bar *D'*, and to the top of the uprights *D D* are attached the pieces *C C*, of soft iron, by means of screws, or in any other proper manner, the inner ends of said pieces *C* protruding through the apertures *A*', and also a short distance into the chamber within the

case *A*', a short distance intervening between the said two inner ends of the poles *C C*.

The lower part of the spiral spring *n* rests upon the shoulder *r*, in the pipe *B*, while the upper part extends upward between the poles *C C*, its upper end pressing upward against the lower side of the armature, or disk *m*, and keeping the conical end *h'* of the valve always against its seat *h*.

The wire *K* is wound around the uprights *D D*, one end connecting with one of the insulated posts *N*, the other end of the wire being connected with the other insulated post *N*.

The whole arrangement of the coil *K*, bar *D'*, and enclosed uprights *D D*, constitute a common soft-iron magnet, when the posts *N N* are connected with a battery.

But this feature I have added, viz., the extension and introduction of the poles of the magnet into the chamber within the case *A*', by means of the pieces *C C*, and the ends of said pieces *C*, which are within said chamber, are a distance apart somewhat less than the diameter of the disk *m*, so that when the circuit of electricity is complete, the said pieces *C C* become the poles of the magnet, and the disk, or armature *m* rests upon the inner ends of said pieces of poles.

The holes *s' s'*, in the lower insulator *F*, are for the insertion of the posts *N' N'*, which may be firmly secured therein in any proper manner, and the holes *s s*, in the upper insulator *E*, are for the insertion of the wires *L L*, which may be of brass or other suitable metal, firmly secured in said holes in any proper manner; and the platina wires, or tips *b b*, are secured at the upper ends of the wires *L L*, and at a suitable distance apart.

The lower side of the disk, or armature *m*, upon the lower end of the valve *o*, is covered with a thin coating, film, or sheet of silver or other non-magnetic substance, to prevent any liability of the said armature *m* to stick to the poles *C C* of the magnet, after the circuit is broken, as might be the case if such coating of silver were not used, owing to some small quantity of electro-magnetism remaining in the armature *m* after the circuit was broken.

It is evident that the passage through the pipe *B* might be of the same size as that portion within which is the spiral spring *n*, and, instead of the permanent shoulder *r*, a small ring might be inserted for the spring *n* to rest upon; and it is also evident that many of the parts might be cast solid, with great advantage as to cost and facility of manufacture, instead of being secured to each other by screw-threads, as shown.

The pipe *B*, spring *n*, armature-case *A*', valve-case *I*, and valve *o*, I prefer to make of brass or other non-magnetic substance, while the armature, or disk *m*, as well as the magnet, should be made of soft iron.

Having thus described the construction of my invention, I will now proceed to describe the mode of its operation.

All the several parts of the apparatus being in place, as shown in figs. 1, 2, and 3, and each end of the coil *K*, at *N' N'*, being properly connected with a battery, the arms *C C* each become a pole of the magnet, and the elastic force of the spring *n* is overcome by the strength of the current, or the force of the magnet, and the armature *m*, secured to the valve *o*, is drawn down to the poles *C C* of the magnet, where it remains as long as the circuit remains unbroken.

This action of the armature *m*, of course draws the conical-shaped valve *o* away from its seat, and communication being then open and uninterrupted through the pipe *B*, passage *i* or *i'*, around the valve-head *h'*, and through the passages *f*' and *x'*, the gas escapes through said passages and out through the burner.

If now, only for an instant, connection is formed between the poles of a Rhumkoff coil, worked by a battery and the poles N N, the circuit is complete, and a current of electricity passes up one of the wires L, across, over the burner, from one platina tip b to the other, through the jet of gas, instantly lighting it, and as long as the circuit is kept up through the coil K, the valve o is held down and away from its seat by the poles O O of the magnet, and the flow of gas continues to flow uninterruptedly to supply the flame, but the instant the circuit is broken, the valve o flies back to its seat, by the elastic force of the spiral spring n, and the flow of gas is instantly stopped.

As, to have this apparatus operate successfully, some degree of delicacy or accuracy of adjustment is necessary in the distance of the disk, or armature m from the poles O O of the magnet, the same is easily accomplished by means of the nut H, as, by turning that either up or down upon the thread g, on the outside of the valve-case I, and then turning said valve-case into the armature-case A², as far as the position of the nut H will admit, the distance of the armature m from the poles O O of the magnet is easily adjusted.

It is obvious that this apparatus may be attached to any number of different kinds of gas-burners, either in buildings or streets, and as, by a proper connection with each other, and with one station or battery, by wires, any number of burners may be lighted at one and the same instant, it is obvious that this apparatus is peculiarly applicable to the lighting of all the street-lamps of a large city, or any number of burners in

large buildings, instantaneously, while it is easy of manufacture, and not liable to any derangement of parts.

It is evident that the insulators may be made of any suitable materials, while other suitable metals possessing the requisite properties may be substituted for those herein described, without departing from the principle of its operation.

I am aware that various arrangements have heretofore been used to both let on and light gas by electricity, but never to my knowledge has the device hereinbefore described been known or used, and I disclaim any and every other device, when considered irrespective of my arrangement and construction; but having described my invention,

What I claim as new, and desire to secure by Letters Patent, is—

1. The combination of the electro-magnet, having the extension-poles C passing through a non-magnetic substance, with the armature operating within a chamber, in the manner substantially as described.

2. An apparatus for letting on and lighting gas by electricity, consisting of the two poles C of a horseshoe magnet, brought within a chamber and operating the valve, the insulator E, burner, and one or more insulated lighting-wires b, all constructed and operating substantially as herein described and specified.

HENRY G. FISKE.
